AUTOMATIC TUNER

Le Roy J. Leishman, Los Angeles, Calif.

Application November 22, 1937, Serial No. 175,916

11 Claims.

(Cl. 74—10)

This invention relates to radio receiving sets and the like, and more particularly to those in which the tuning control shaft is turned to predetermined angular positions by semi-automatic means. Among its objects are conservation of space, simplicity of construction, the provision of means whereby it is rendered difficult to see the apparatus through apertures in the escutcheon, the illumination of the station index tabs by the same bulbs illuminating the dial, the exclusion of light from the semi-automatic operating mechanism, and the provision of a manual tuning control that does not make the semi-automatic controls more difficult to operate. Still other objects will appear as the description proceeds.

In the accompanying drawings:

Fig. 1 is a side elevation of my device, with part of the radio chassis cut away to reveal the construction more clearly.

Fig. 2 shows the design of the operating levers and positioning cams, together with their relation to the top cover of the device.

Fig. 3 is a side elevation of the frame for the mechanism, showing the pulleys and gears that are on the opposite side to that shown in Fig. 1.

Fig. 4 is a front elevation with various parts cut away to reveal the construction more clearly.

Fig. 5 is a plan view of the manual drive of Fig. 4.

Fig. 6 is a perspective view of a chassis, stamped out to accommodate the automatic tuning device.

Fig. 7 illustrates a novel means of attaching the tuning mechanism to the indicator for a vertical tuning scale.

Fig. 8 is a front elevation of a horizontal tuning scale, showing an improved pulley system for connecting the indicator to the tuning mechanism.

Fig. 9 is a side elevation of the pulley arrangement shown in Fig. 7.

When a lever-operated tuning mechanism is placed on top of the chassis, with the currently-popular, large round dial above the tuning mechanism, the distance from the bottom of the chassis to the top of the dial is too great for average-height table model receiving sets. This invention makes it possible to put the lever-controlled operating mechanism on the underside of the chassis, thus greatly reducing the over-all height of the complete assembly. Placing the mechanism under the chassis is also an aid in keeping light from the dial-illuminating lamps from illuminating the apparatus and making it visible through the lever slots in the escutcheon.

In Fig. 1, W is the chassis having a top B (partly shown in section) to which is attached the top plate D of the tuner assembly frame by means of screws E and nuts F.

In the form shown in the drawings, the frame is constructed from two pieces—part I, which forms the side in which the short shafts for gears L and Y are journaled; and a second part having

a long side C, a short side T, and a horizontal top section D connecting sides T and C. Shafts S and Q are journaled at one end in the side, or end-plate, C, and at the other end in plate I.

The semi-automatic tuning mechanism proper, shown in Fig. 2, is a modification of the mechanism illustrated, described and claimed in my co-pending application, Ser. No. 154,819. The alterations in this mechanism reduce its space requirements and permit accurate operation without accurate workmanship in the manufacture of the parts. Operating lever F is provided with a mid-section having a flat upper edge 2 that normally is held against abutment P by spring J fastened in holes 3 in the drawn portion 4 of plate D. This portion is depressed so that the hooks on the ends of the springs will not extend above the top surface of plate D. The abutment P may be made of rubber or other resilient material, and is cemented or otherwise attached to the under side of plate D.

At portion 6, Fig. 2, lever F forms substantially the same angle with positionable member A in the illustrated upward position as it does in the form shown in Fig. 3 of my co-pending application above referred to. In front of position 6, the lower edge of lever F curves downward as shown at 5. As lever F is pressed down, causing end 7 of positionable member, or lever, A to move outward along lever F, the angle between the two engaging levers is such that lever A moves easily despite the downward curve or arch 5 in the lower edge of lever F. When lever F is depressed as far as it will go, arch 5 serves a very useful purpose. This extreme position of an operating lever is shown by lever F¹, Fig. 2, cooperating with positionable lever A¹. The movement of lever F¹ has turned member A¹ until the two levers are in engagement at two points 8 and 9. Arch 5a of lever F¹ is seen to be curved away from the substantially straight adjacent edge of member A¹, assuring that the engagement between the two cooperating levers will be at points 8 and 9 only. This obviates the possibility of manufacturing inaccuracies causing these levers to engage at some intervening point, thus destroying the precision of the angular position to which member A¹ is always turned when lever F¹ is pressed all the way down.

The center portion 11a of positionable member A¹ is split through the hole that admits shaft S in order to form a clamp for affixing member A¹ to the shaft in any desired angular position. When the operating lever is pressed all the way down, thus rotating member A¹ to the position shown, it will be noted that the clamping screw R¹ is substantially horizontal and parallel to the top plate D.

A plurality of operating levers, preferably having buttons 65 on the free ends, are mounted

on rod Q, and each operating lever cooperates with one of a series of positionable members on shaft S.

In Fig. 1, a positionable lever A2 is shown in an angular position 180 degrees opposite from that occupied by positionable member A as illustrated in Fig. 2. It will be noted that the rounded end K2 is so shaped that the downward movement of lever F will cause positionable member A2 to assume the position shown in dotted lines. This is the tuned-in position just described in relation to Fig. 2—the position at which the further downward movement of the operating lever is arrested by engagement with the positionable lever at two points lying on opposite sides of the shaft S.

The motion of shaft S must be transmitted to the impedance varying means—in this case the gang condenser 21, Fig. 4, and to the tuning scale or indicator.

The connection to the condenser is effected by means of gear 12, Fig. 4, attached to shaft S by screw 13 in hub 14; idler gear Y, Figs. 1, 3 and 4, meshing with gear 12; gear L, meshing with gear Y, and attached to shaft 15 journaled in end-plate I; and the coupling 16 attached to shaft 15 and the condenser shaft 17. Pulleys 18 and 19, having a 1-2 ratio, are attached to gears L and 12 respectively, which also have this same ratio respectively. Since the type of semi-automatic tuning mechanism illustrated in Figs. 1 and 2 turns only 90 degrees, this ratio is necessary to produce the required 180 degree rotation of the condenser. Cord 20 is attached to pulley 18 and to spring 23, which in turn is connected to cord 22 attached to pulley 19. The tension of spring 23 takes the play out of the gear train.

The transmission to the dial or pointer can best be explained with reference to Fig. 4. This figure is a front view of part of a radio set with portions of the escutcheon, cabinet, and light-excluding mask (to be explained later) cut away in order to show pulleys 24 and 25 fastened on shaft S on either side of the center positionable lever A by means of pins 26 and 28 respectively in short hubs 27 and 29 respectively. A cord 30 is attached to pulley or reel 24 at point 31 and to pulley 32 at a point not shown. Cord 34 is also attached to pulley 32 at point 33, but is reeled around the pulley in an opposite direction to that of cord 30. Cord 34 is fastened to spring 35, which is attached at its opposite end to cord 36. Cord 36 passes around pulley 25 as indicated in the figures and is attached to this pulley at a position not shown. Spring 35 keeps the cords taut. Pulley 32 is attached to shaft 37 by means of set-screw 38. Shaft 37 may be attached to a rotating dial, or, as shown in Fig. 1, to an indicating hand 39, which requires that the shaft pass through the center of dial 40. Pulley 32 may have any desired ratio with respect to pulleys 24 and 25 in order to move the indicating hand around the calibrated portion of the dial during the 90 degree rotation of shaft S.

Cords 30 and 36 pass through holes in plate D of the tuner assembly frame, and through slots 42 and 41 respectively in the top of the chassis, shown in Fig. 6, which illustrates how the chassis is cut to accommodate the tuner assembly.

To operate a tuner of this type, it is desirable that very little pressure be required on the operating keys. The conventional types of drives between the manual tuning knob and the condenser shaft add enormously to the pressure that the operator's finger must exert in order to move the interconnected mechanism. This in-

vention provides a simple means whereby the manual drive is disconnected excepting when the operator is actually using the tuning knob. A beveled-edged wheel 43 is mounted on shaft S as indicated in Figs. 1, 4 and 5. A small wheel 44 having a rim of rubber or other material with suitable frictional properties is carried by a shaft 45 passing through holes 46 and 47 in the outer ends of bracket 48 attached to plate C of the tuner assembly frame. A collar 49 is attached to shaft 45 by pin or screw 50. An expansion spring 51 is coiled around shaft 45. One end of this spring is supported against end 52 of bracket 48, and the other end of the spring forces collar 49 against end 53 of the bracket, as shown in Figs. 1 and 5. In this position of the shaft, the rim of wheel 44 is just out of engagement with the beveled edge 54 of wheel 43. The manual tuning knob 55 is preferably so shaped that the operator's fingers naturally press against it in order to secure a firm grip. This pressing action causes wheel 44 to engage the bevel of wheel 43, and the rotation of the knob thus turns wheel 43 and the interconnected tuning condensers and dial.

One of the objects of this invention is to keep the light that illuminates the dial from illuminating the automatic tuning mechanism, as the mechanism is then visible through the lever slots in the escutcheon. Since the dial lamps are above the chassis, the placing of the lever mechanism below the chassis eliminates the greater part of this light, but still additional means have been provided for its exclusion. A mask, or sub-escutcheon, 56 is attached to the front of the tuner assembly in any suitable manner. This mask has slots G1 for the levers and holes 57 for adjusting the positionable lever set-screws in a manner to be explained later. The mask 56 preferably extends above the chassis. The front plate or escutcheon 58 carries a perpendicular member 59 which serves the two-fold purpose of registering the escutcheon with the levers and adjusting screws regardless of the separation between the escutcheon and chassis, and of keeping light from above the chassis from shining through the slots in the escutcheon. This perpendicular member 59 rests on the top edge of mask 56, and the right end of the perpendicular member abuts against bracket 60, as shown in dotted lines in Fig. 4. The portion of mask 56 that extends above the chassis not only forms part of the registering means, but also serves to keep light from the dial illuminating lamps 61 from passing beneath member 59. The greater portion of the sub-escutcheon lying beneath the top of the chassis acts as a two-way mask. A certain amount of light from outside the radio set naturally passes through the slots G in the front escutcheon and spreads out at a rather wide angle on the reverse side of the escutcheon. None of this light can reach the tuning mechanism except the small portion that passes through the slots G1 in the mask. In similar manner, the mechanism is rendered more difficult to see from the outside of the set because of the very narrow angle that would be visible through two slots in alignment as compared with only one.

Each operating lever is provided with a translucent index tab O, Figs. 1 and 4, resting in a recess 62, Fig. 1, between plate M and escutcheon 58. Plate M is provided with a window N for each index tab. Lamps 61 that illuminate the dial also illuminate the index tabs.

To "set" the tuner so that each lever will tune

in a predetermined station, plate 63 is removed from the escutcheon by taking out screws 64—one on each end of the plate. This exposes holes U in the escutcheon which register with holes 57 in the sub-escutcheon. One of the operating levers is then pressed down as far as it will go. This brings the set-screw R of the cooperating positionable member into alignment with these holes. A screw-driver is then inserted through holes U and 51, and set-screw R is loosened. This permits shaft S to turn freely while the positionable member is being held stationary by the pressure of the operating lever, which the operator continues to hold down. The desired station is then tuned in manually by means of knob 55. After the station is tuned in as perfectly as possible, the set-screw is again tightened. This procedure is repeated with each lever until they have been "set" to tune in the operator's favorite stations. From the description already given of the workings of the operating levers and positionable members, it will be obvious that the subsequent pressing of any lever will perfectly tune in the station for which the setting was made.

Buttons 65 are removable from the ends of the operating levers, permitting the levers to pass freely through the slots G in the escutcheon. When this feature is borne in mind, it will be evident that the tuning unit without the escutcheon may be completely assembled before mounting it on the chassis. The assembly frame of the tuner is provided with a rod or support 66 running from plate I to plate C to give it rigidity. This rod is omitted from Fig. 4 to avoid confusion with the other parts shown.

Part I of the assembly frame has a top section 67 bent at a right angle to the portion of member I that supports the gears. Section 67 is 40 stamped with projections 68 and 69 that are turned to form the bracket in which the dial-shaft 37 is journaled. Bracket 60 may be stamped from the piece of metal forming the main body of the tuner frame, or it may be a separate piece. 45 In the form shown in the drawings, bracket 60 is integral with the frame, and is bent at the top to form a brace 70 for attachment in any suitable manner to member 67.

Fig. 6 illustrates how the chassis is stamped 50 to receive the tuning unit. As already explained, slots 41 and 42 permit cords 36 and 38 respectively to pass. Slot 71 is for side I of the tuner frame. Hole 72, Fig. 6, receives bolt 74, Fig. 4, which also passes through hole 75, Fig. 3, in bracket 76, Figs. 3 and 4, formed on part I. Hole 73 in the chassis, Fig. 6, registers with hole 77, Fig. 3, in bracket 78 on member I to receive a bolt for attaching the tuner assembly to the chassis. Holes 79 and 80 in the chassis, Fig. 6, 55 are to receive screws E, Fig. 1.

Fig. 7 shows the means and method of connecting the tuning unit to the indicating pointer for a vertical tuning scale. All parts of the unit have been omitted with the exception of shafts S, Q and 15 so that the relationship of these pertinent parts will not be obscured by other parts of the tuner. In this embodiment of the invention, a series of operating levers are mounted on each end of rod Q on opposite sides of the vertical scale 81, and a series of positionable members are similarly mounted on each end of shaft S. The gang condenser should be positioned behind the vertical scale. Pulley 82 is mounted on shaft 15 and carries cords 83 and 84 which pass around pulleys 85 and 86 respectively. Cord

83 is attached to the pointer-mounting 87 of pointer 88. One end of the cord-tightening spring 89 is also attached to the pointer mounting, and the other end of the spring is fastened to cord 84. It will be noted that the construction is such that the cords will avoid other parts of the mechanism, because cord 84 passes between shafts S and Q. This construction is very simple and provides a drive from the tuning mechanism to the pointer that adds very little friction, as there are only three pulleys in all.

Fig. 8 illustrates a drive for a horizontal scale. Such a scale should preferably be placed above the tuning levers. In the figure, all parts of the tuner have been omitted with the exception of those that show the relationship of the parts associated with the drive for the pointer. Pulley 82 is shown on shaft 15 between pulley 18 and coupling 16, which are located, along with the gang condenser, in the same positions shown in Fig. 4. Pulley 82, Figs. 8 and 9, carries a cord 84, fastened at a position 91. After passing under pulley 82, this cord passes over pulley 86 and thence to a connection with pointer-mounting 92 for pointer 88 adapted to move along horizontal scale 94. Cord 83 is connected to the other end of the pointer mounting and passes around pulley 90 and then to cord-tightening spring 89. The other end of this spring is connected to one end of cord 84, which then passes around pulley 85 and thence to pulley 82.

Although the preferred form of my invention contemplates the use of the lever-operated tuning mechanism hereinbefore described, other automatic or semi-automatic tuning mechanisms may be used beneath the chassis without departing from the spirit of the invention. Various modifications, omissions, additions or substitutions are possible within the broad scope of this invention of which this specification describes only typical embodiments.

My claims are:

1. In a device for positioning a control of a radio set, a combination including: a supporting element; an escutcheon positioned substantially at right angles to said supporting element; a rotatable shaft positioned beneath said supporting element and lying substantially parallel to said escutcheon and to said supporting element; a calibrated scale and indicator positioned above said supporting element; means for varying the relative position between said indicator and the calibrations on said scale in accordance with the angular position of said shaft; and a member extending substantially perpendicularly from said escutcheon; said member and said supporting element overlapping.

2. In a device for positioning a control of a radio set, a combination including: a supporting element; an escutcheon positioned substantially at right angles to said supporting element; a rotatable shaft positioned beneath said supporting element and lying substantially parallel to said escutcheon and to said element; a calibrated scale and indicator positioned above said element; means for varying the relative position between said indicator and the calibrations on said scale in accordance with the angular position of said shaft; means for illuminating said scale; and a member extending substantially perpendicularly from said escutcheon; said member and said element overlapping.

3. In a device for positioning a control of a radio apparatus, a combination including: a supporting element; a rotatable shaft positioned be-

- neath said supporting element and lying beneath and, substantially parallel to said element; a plurality of operating levers pivoted beneath said element; means for rotating said shaft upon the movement of any of said levers in one direction; a mask having a plurality of slots each adapted to permit one of said levers to pass therethrough; and an escutcheon substantially parallel to said mask and having a series of slots substantially in register with the slots in said mask.
4. In a radio communication device having an assembly plate, a combination including: a frame mounted on said assembly plate and supporting a rotatable element; a bracket attached to said frame and extending through the plane of said plate; an escutcheon having a registering member extending substantially perpendicularly therefrom; said member having one edge abutting against said bracket.
5. In a mechanism for angularly positioning a control element of a radio device, a combination including: a rotatable shaft; a positionable lever mounted on said shaft; a pivoted operating member having a curved edge adapted to be longitudinally traversed by one end of said positionable lever; said curved edge forming an arch between the points of engagement with said lever when said member is in the extreme position to which it may be moved.
6. In a mechanism for angularly positioning a control element of a radio device, a combination including: a rotatable shaft; a positionable lever mounted on said shaft; a pivoted operating member having a curved edge adapted to be longitudinally traversed by one end of said positionable lever; said curved edge forming an arch between the points of engagement with said lever when said member is in the extreme position to which it may be moved; and means for clamping said lever on said shaft, said means including a tightening screw; said screw forming an angle with a line connecting said points.
7. In a mechanism for angularly positioning a control element of a radio device, a combination including: a train of gears; a first pulley attached to the gear at one end of said train; a second pulley attached to the gear at the opposite end of said train; said pulleys concentric with the gears to which they are attached and having the same ratio as said gears; a flexible connection between said pulleys; and means for keeping said connection taut, whereby the play in said gear train is removed.
8. In a mechanism for positioning a control of a radio apparatus, a combination including: an assembly frame; a rotatable member located inside said frame and disposed substantially parallel to the top thereof; a plurality of manually movable station selectors extending through a cover plate substantially perpendicular to the top of said frame; a plurality of angularly adjustable elements each operatively interposed between one of said selectors and said member and adapted upon movement of the associated selector to rotate said member to a position predetermined by the adjustment of said element; a resonance-varying device located above said frame; and instrumentalities for transmitting rotary motion from said member to said device, said instrumentalities comprising a first rotatable element attached to said member, a second rotatable element attached to said device, a third element operatively interposed between said first and second elements, and means for removing play from said instrumentalities.
9. In a mechanism for positioning a control of a radio apparatus, a combination including: an assembly frame; a rotatable member located inside said frame and disposed substantially parallel to the top thereof; a plurality of manually movable station selectors extending through a cover plate substantially perpendicular to the top of said frame; a plurality of angularly adjustable elements each operatively interposed between one of said selectors and said member and adapted upon movement of the associated selector to rotate said member to a position predetermined by the adjustment of said element; a resonance-varying device located above said frame; and instrumentalities for transmitting rotary motion from said member to said device, said instrumentalities comprising a first rotatable element attached to said member, a second rotatable element attached to said device, a third element operatively interposed between said first and second elements, and means for removing play from said instrumentalities; said means comprising a spring having a connection to said first and second elements.
10. In a mechanism for positioning a control of a radio device, a combination including: a rotatable member; a plurality of independently operable position selectors; a plurality of elements each operatively interposed between one of said selectors and said member, and each adjustable with respect to said member in a plane substantially transverse thereto; each of said elements adapted upon operation of the associated selector to rotate said member to a position predetermined by the adjustment of said element; a tuning scale positioned symmetrically above said plurality of position selectors; an indicator adapted to cooperate with said scale; and means for producing relative motion between said scale and indicator upon rotation of said member; said means including a component fixed to said shaft between the planes of adjustment of two of said elements.
11. In a radio tuning apparatus, a combination including: an assembly frame; a positionable member rotatably mounted in said frame; a cover plate substantially parallel to said member; a plurality of manually movable station selectors extending through the plane of said plate; a plurality of angularly adjustable elements each operatively interposed between one of said selectors and said member and adapted upon movement of the associated selector in one direction to rotate said member to an angular position predetermined by the adjustment of said element; a resonance-varying device supported by said frame; a rotatable control for said device; and instrumentalities for transmitting rotary motion from said member to said control, said instrumentalities comprising a first rotatable element connected to said member, a second rotatable element attached to said device, a third element operatively interposed between said first and second element, and means for removing play from said instrumentalities; said means comprising a spring having a connection to said first and second elements.

LE ROY J. LEISHMAN.
